UNITED STATES PATENT OFFICE.

FRANK ENGEL, OF BUFFALO, NEW YORK, ASSIGNOR, BY MESNE ASSIGNMENTS, TO U. S. LIGHT & HEAT CORPORATION, OF NIAGARA FALLS, NEW YORK, A CORPORATION OF NEW YORK.
MACHINE FOR FORMING STORAGE-BATTERY PLATES.

1,190,988.

Specification of Letters Patent. Patented July 11, 1916.

Application filed November 14, 1907. Serial No. 402,164.

To all whom it may concern:

Be it known that I, FRANK ENGEL, a citizen of the United States, residing in the city of Buffalo, in the county of Erie, State 5 of New York, have invented certain new and useful Improvements in Machines for Forming Storage-Battery Plates, of which the following specification and accompanying drawings describe and illustrate one 10 embodiment.

The invention relates to machines for forming lead plates or units for use in storage batteries. Such plates are frequently formed by casting under pressure, but this 15 process is objectionable for several reasons. First, it involves an excessive amount of care and labor; second, notwithstanding the exercise of great care, imperfect castings are frequently produced. Furthermore, cast 20 lead itself is not well adapted to endure long use, for the reason that it lacks the requisite compactness and density. Lead battery plates are also sometimes produced by a spinning process in which the blanks are 25 subjected to circular knives rotated at considerable speed, the peripheries of the knives being driven through or caused to cut the surface of the plate, but this spinning process also has notable disadvantages, one of 30 which is due to the fact that the knives put the metal under tension, thus tending to pull the molecules apart and decrease the density of the plates. The result is that the product is more susceptible to the action of the 35 acid, which produces irregular growth and buckling. Furthermore, the knives soon become worn and produce a ragged cut which affords further access to the acid. Moreover, the knives are necessarily so large in 40 diameter that they give sloping sides to the metal at the beginning and end of a cut. The advantage of the configuration shown herein is that the plate has greater contact surface in proportion to its weight and 45 therefore has its capacity increased in proportion.

The best battery plate is one having great and substantially uniform density, free from irregularities of outline and the presence 50 of foreign matter and provided at regular intervals with accurately formed cross-bars for strengthening the fins or ribs. It is also essential that the fins should be of substantially uniform density out to their

edges and that the edges should be of uniform height and configuration.

The object of my invention is to produce an organized mechanism capable of producing plates having these desirable characteristics.

The object also is to produce a machine in which the acting parts are subjected to a minimum wearing action so that they may accurately maintain their configuration during a long period of use and consequently 65 always produce a uniform product. As contributing to this latter characteristic, it is a purpose of the invention to distribute the stresses and strains during action as uniformly as possible throughout the cycle of 70 operation and to produce a plate by successive pressing actions gradually increasing in intensity.

The preferred program of operation in general consists in subjecting the blank to 75 substantially a rolling pressure produced simultaneously on opposite faces of the blank by a pair of coöperating dies or formers which oscillate back and forth and are gradually forced closer and closer together 80 to finally bring out the desired configuration and density of the plate. In the preferred form of machine, the blank, instead of deriving its reciprocating movement from the action of the formers, is operated positively by a reciprocating support or holder, operating in timed relation with the formers and thus positively controlling the movement of the plate and enhancing the accuracy with which the plate is formed. Cross- 85 bars of any desired configuration are produced simultaneously with the production of the fins by means of notches in the blades constituting the acting surfaces of the formers. As a result of this repeated rocking 90 or pressing action of the formers upon the blank, the density of the lead is materially increased and may be regulated to a nicety by varying the shape of the formers and the distance to which the coöperating surfaces 95 thereof approach each other in their nearest position. Moreover, by properly proportioning the former plates and spreaders or separators, the cores, fins and cross- 100 ribs may be subjected to the different degrees of pressure required. As a result of the operation of the mechanism, the plates 105 are dense at all parts and particularly in the

outer strata, are accurately formed and do not vary one from another to any appreciable extent by reason of the wear of the acting parts.

5 The invention will be more fully disclosed by referring to the following description, taken in connection with the accompanying drawings, in which is illustrated, in a convenient and practical form, one of the 10 various possible embodiments of the invention.

In the drawings, Figure 1 is a view in side elevation of the machine chosen for illustration of the invention; Fig. 2 is a plan view 15 thereof; Fig. 3 is a view in end elevation; Figs. 4 and 5 are detail views on a larger scale of a set of formers; Figs. 6 and 7 are detail views of a battery plate produced by the improved machine.

20 In the machine shown in the drawings, there is mounted upon a suitable frame or housing *a*, a crank-shaft *b*, driven in any suitable manner; the crank *b'* thereof being connected by a pitman *b*² with a cross-head *c*, which is supported to slide to and fro upon ways *a'* on the frame *a*. A support or holder *d*, having an opening *d'* therein to receive snugly the blank lead plate *e*, is mounted in suitable ways *a*² in 25 the frame and is connected to the cross-head *c* by any suitable means, as by a pin *f*, so as to be reciprocated therewith. The opening *d'* in the plate-holder is adapted to accommodate a blank $3\frac{3}{16} \times 3\frac{5}{16}$ inches in 30 the machine illustrated, which blank is a tight fit in said opening and is held therein frictionally after being pressed in by hand. When it is desired to use a large machine and a larger blank of considerable weight, 35 any suitable means may be employed to hold said blank in the opening and prevent it from falling through. In the case of either a large blank or a small one, the effect of the opposed formers is to tend to 40 spread the blank as soon as the blades begin to embed themselves therein so that there is firm frictional engagement between the edges of the blank and the walls of the opening in the holder. The holder *d* may 45 be provided with a hand-hole *d*² by which it may be withdrawn from the machine when disconnected from the cross-head.

In the machine shown in the drawings, 50 the lead blank *e* is subjected simultaneously on opposite sides to the pressing action of two sets of formers. As shown in Figs. 4 and 5, each set is made up preferably of thin blades or ribs *g* with curved gradually tapering edges, which are notched at intervals, as at *g'*, alternating with separators *g*² shorter than the blades, outside supporting plates *g*³ and bolts *g*⁴ and *g*⁵ by which the blades and separators are firmly bound together between the plates *g*³ although I do 55 not limit myself to this construction. Each

set of formers is pivotally mounted, as by means of the extended bolt *g*⁶ in a block *h*, movable toward and from the holder *d* in suitable ways in the frame *a*. Each block *h* is suitably connected so as to permit the necessary relative movement to an eccentric block *i* by means of bolts *j* sliding in elongated slots *j'* in the block *i*, which block is mounted on an eccentric *k'*, formed on a shaft *k*, which is supported in suitable 70 bearings in the frame. The shafts *k* are rotated slowly so as to cause the sets of blades to approach each other slowly by any suitable means, as for example, by worm-gearing *k*², shaft *k*³, worm-gearing *k*⁴, shaft *k*⁵, and beveled gears *k*⁶ from the shaft *b*. 75

The sets of formers are oscillated in synchronism with the reciprocations of the blank *e*, and for this purpose the two sets of formers may be provided with arms *l* 80 which overlap and are connected in the center plane of the plate *d*, as at *l'*, with links *m*, which in turn are connected to the reciprocating cross-head *c*.

The operation of forming battery plates 85 or units with the machine described will now be readily understood. A blank *e* having been inserted in the opening of the holder *d* and the sets of formers having been drawn apart, the holder is slipped into the 90 ways *a*² provided therefor in the frame *a*, and is coupled to the reciprocating cross-head *c*. Power being then applied to the shaft *b*, the holder *d* with the blank *e* is reciprocated and the sets of formers are oscillated in 95 synchronism therewith. At the same time, the formers are caused to approach each other slowly so that the blades act upon the blank with a rocking motion and gradually displace the lead in a direction from the center 100 core of the plate toward the axes of the formers.

The working edges of the blades have a long taper or bevel, as shown in Fig. 5, as a result of which construction the lead is 105 gradually compressed between adjacent beveled surfaces as it is forced up from the blank until it is reduced to such a thickness that it can pass up between the parallel sides of adjacent blades as continuous new portions 110 of the blank are being wedged between said blades. The gradual compression of the lead as the rib is forced up between the bevels of adjacent blades, closely compacts and increases the density throughout the entire rib, which is very thin, without disrupting or tearing the metal. If the blank is of proper thickness, the lead will be displaced as described until it comes in contact with the edges of the separators *g*², so 115 that the fins or webs of the finished plate shall be of uniform height above the center core and shall have their tops, as well as their sides, consisting of dense metal. Although the blades are illustrated as having 120

125

a substantially uniform or straight line taper at their peripheries, I do not limit myself to this precise form of taper, as it is obvious that a section of the end of a blade 5 may have any one of a number of outlines as long as the desired compression of the blank between adjacent blades is secured without disrupting the metal of the blank.

As will be apparent from Fig. 4, the 10 blades g have as a working edge a relatively short arc, and the notches g' in said edges provide for the formation of the reinforcing cross-bars or cross-ribs e' , which support the fins or webs e^2 , raised from the 15 center core e^3 of the plate e , as shown in Figs. 6 and 7.

The parts of the formers and the eccentrics which cause them to approach each other, are preferably so proportioned with 20 reference to the thickness of the blank operated upon that the side plates g^3 reach the surface planes of the holder d at substantially the same time that the displaced lead, forming the fins or webs of the plate, reaches 25 the edge of the separators g^2 so that the plate e is finished as to its frame e^4 practically simultaneously with the finishing as to the webs e^2 , the entire plate, and particularly the tops of said webs, being subjected to whatever final compression may be 30 desired, as determined by the distance between said formers in their closest position to each other. It will be observed that the center core e^3 is not displaced toward one 35 side or the other of the said plate, but retains always its true position, and furthermore as the edges of the blades g are not dulled by rotation in contact with the lead plate, but act always with a rocking action, 40 the spaces between the webs or fins e^2 terminate with an acute angle in cross section so that the exposure of the center core to electrolytic action is a minimum.

The effect of the small arc constituting 45 the working edge of the former, described above, which arc is long enough, however, to rock upon the blank from one end to the other, as seen in Fig. 1, as compared to a circular disk having a proportionately 50 smaller radius to provide a circumferential working edge of a length equal to this same blank, is to reduce to a minimum the tendency of the blank to roll out or lengthen unduly and cause distortion. A further effect, in view of the relative length or radius 55 of the former, as compared to the length of its working arc and the infinitesimal advance of the formers into the blank at each reciprocation, is that the line of pressure of 60 the formers against the blank is substantially normal to the surface of the blank and not at a considerable angle from the normal, as is the case where a roll or cylindrical former of correspondingly small radius is used.

In order that the formers may be withdrawn rapidly after the completion of a plate, means may be provided for rotating the eccentrics k' independently of the driving mechanism. Thus worm-gears k^2 may 70 be engaged with the shafts k through ball or roller clutches indicated at k' so as to drive the shafts positively but permit the shafts to be rotated forwardly with respect to the worm-gears, while the opposite ends 75 of the shafts k are provided with sprocket-wheels n connected by chain n' , and one of the shafts k is preferably provided with a crank n^2 . The shafts k , with their eccentrics k' , may thus be given a half rotation 80 simultaneously as soon as a plate is completed so as to withdraw the formers rapidly and permit a new blank to be substituted for the completed plate.

I do not herein claim the battery plate or 85 grid which this machine produces, nor the process by which the plate or grid is produced, for these form the subject-matter of a separate application, Serial No. 479,070, filed by me February 20, 1909.

It is obvious that various instrumentalities may be combined to produce the result obtained by the machine selected for the purpose of illustration, and therefore I do not limit myself to the structural details described, but desire to include broadly any suitable means for accomplishing the desired result and included within the scope 95 of the appended claims.

What I claim as new and desire to secure 100 by Letters Patent of the United States is:—

1. A machine for refining the crystalline structure of lead blanks and increasing the superficial area thereof, including means for supporting a lead blank, means operating on opposite sides of said blank to alternately apply pressure and release the same, said means comprising formers each having an arcuate outline to engage said lead blank, and having narrow parallel ribs with tapering edges spaced apart distances substantially equal to the width of the ribs, the parallel walls of adjacent ribs forming between them pockets having flaring openings formed by the tapering edges of the 110 ribs and means for positively gradually advancing said first means toward each other an infinitesimal distance at each operation thereof, the ratio between the radius of said arcuate outline and the advance at each operation being so great that the line of pressure on said plate is practically normal to said plate, whereby the lead of the blank may be uniformly kneaded and refined by the repeated application of pressure, and 115 whereby the lead of the blank displaced by said ribs may be formed into ribs or fins by being gradually forced into said pockets, the flaring openings of said pockets serving to densify and consolidate the ribs or fins 120 125 130

- as the lead is forced therethrough without disrupting or tearing the lead.
2. In a machine for making Planté battery plates, the combination of a reciprocable blank carrier and a pair of rocking formers, one on each side of said blank, each former being provided with thin parallel blades separated by narrow spaces, the working edges of said blades having a slight curvature to permit said formers to be gradually pressed into said blank with a rocking motion, the radius of curvature of the working edges being so great, and the distance the blades are pressed into the blank at each reciprocation being so small that the acute angle formed between the direction of pressure on the metal and the surface of the blank is always greater than the angle of pressure which will cause the metal to be pressed forward in the direction of reciprocation of the blank, whereby the metal is gradually forced between the blades to form ribs of density greater than the original density of the blanks.
3. In a machine for making Planté battery plates, the combination of a reciprocable blank carrier, a pair of rocking formers, one on each side of said blank, each former being provided with thin parallel blades separated by narrow spaces, the working edges of said blades being tapered in the form of an acute angle and having a curvature of large radius as compared to the length thereof, and means for gradually pressing said tapered blades into the blank, the radius of curvature of the working edges being so great relative to the distance the blades are advanced at each reciprocation that the angle formed between the radius of the blades, co-incident with the direction of pressure on the blank and the radius normal to the blank surface, is always less than the angle beyond which if pressure is applied to the blank the metal of the blank will be displaced in the direction of reciprocation of the blank, the coördination of the parts producing lateral displacement of the metal of the blank by said tapered edges and compressing and densifying the metal between said blades as the same are advanced into the blank.
4. In a machine of the character described for producing Planté battery plates from a lead blank, means for supporting the blank, a pair of opposed formers having working faces substantially equal in length to the blank, said faces being curved on an arc of radius not less than the length of said faces, and means for simultaneously rocking said formers in contact with the blank and advancing the formers toward said blank through small increments, whereby pressure may be applied to the opposite faces of the blank substantially at right angles thereto to prevent the metal from rolling out ahead of said curved faces while consolidating said metal and rendering its crystalline structure finer and more uniform.
5. In a machine of the character described for producing a battery plate grid from a lead blank, means for supporting the blank, a pair of opposed formers having thin curved projecting ribs forming working faces, means for reciprocating said blank supporting means and oscillating said formers through ninety degrees or less to rock the working faces over the surface of the blank and exert pressure at substantially right angles thereto, and means for advancing said formers toward each other a small amount at each actuation thereof.
6. In a machine for making Planté battery plates, the combination of a reciprocable blank carrier, a pair of rocking formers, one on each side of said blank, and means for advancing said formers toward each other by small increments, each former being provided with thin parallel blades separated by narrow spacers providing spaces of substantially equal depths, the working edges of said blades being sharpened and slightly curved away from said blank, these elements being so coördinated that the metal is kneaded in forming the ribs.
7. In a machine of the character described for making a battery plate grid from a lead blank, means for supporting the blank, rocking formers adjacent the opposite sides of said support provided with gradually curving surfaces having a plurality of gradually tapered working edges with intervening spaces, and means for simultaneously rocking said formers through an angle of less than ninety degrees and advancing the same toward the blank by small increments whereby the surfaces of said blank may be alternately compressed by pressure exerted substantially normal to the surface of the blank and the pressure thereon relieved so as to knead the lead, thereby consolidating and refining the same and gradually working the lead into the spaces between said working edges to form symmetrical ribs of uniform texture and density without disrupting or tearing the lead.
8. In a machine of the character described for making Planté battery plate grids from a lead blank, means for supporting the blank, opposed pivoted formers mounted for rocking engagement with opposite faces of a blank on said supporting means, each former comprising alternate thin sector-shaped blades and sector-shaped spacers therebetween, the radius of curvature of the curved edge of each former being relatively great and the edge of each former extending through less than ninety degrees of a circumference, means for rocking said formers and reciprocating said blank support in unison, said means rocking said formers through an angle of less than ninety degrees.

5   degrees, and automatic means for advancing said formers toward said blank by a small increment at each reciprocation of said blank support, the ratio between the radius of the
 10   formers and the advance at each operation being so great that the line of pressure on said blank is practically normal to said blank, whereby the various elements co-operate to knead and refine the opposite surfaces of the blank and to gradually work the lead between the blades to form symmetrical ribs on opposite faces of the blank without disrupting the lead.

15   9. In a machine of the character described, means for supporting a lead blank, and opposed formers mounted for rocking engagement with opposite faces of said blank, each former comprising thin sector-shaped blades of equal radius and sector-shaped spacers concentric therewith, said spacers having equal radii, less than the radii of the blades, and means for simultaneously rocking said formers and slowly advancing the same toward the blank to form
 20   uniform ribs on opposite faces of said blank, whereby said ribs are limited and rendered uniform in height and the upper faces of said ribs being finished by said sector-shaped spacers.

25   10. In a machine for making Planté battery plates, a former comprising thin sector shaped blades, the working arcs thereof subtending an angle of 90 degrees or less, and thin spacers interposed between said blades, said spacers having working edges of equal radius less than the radius of said blades and concentric therewith.

30   11. A former for battery plates, comprising alternate blades and washers bound together by a plurality of bolts, one of said bolts constituting a bearing axle for said former, another bolt serving for the attachment of a driving connection.

35   12. In a battery plate machine, in combination, a pair of opposed oscillating formers adapted to produce a battery plate each comprising blades having gradually tapering working edges and having radii relatively large as compared with the length of said edges, a blank holder mounted to reciprocate between said formers, a driving member,

means connecting said driving member with each of said formers and with said blank holder, whereby said formers are oscillated and said blank holder is reciprocated in unison therewith, and means for slowly advancing said formers toward said blank holder, the ratio between the radius of said blades and the advance at each operation being so great that the line of pressure on said blank is practically normal to said blank, whereby
 40   said gradually tapering blades are embedded in opposite sides of the blank in said blank holder to gradually displace the metal thereof in the form of uniformly dense compact ribs by pressures exerted substantially normal to the surfaces of said blank, whereby
 45   said displaced metal is not disrupted.

50   13. In a battery plate machine, in combination, a housing, a pair of opposed oscillating formers adapted to produce a battery plate mounted in said housing each former comprising blades having interposed washers and having gradually tapering working edges extending beyond said washers, said blades having relatively long radii
 55   as compared with the length of said edges, a blank holder also mounted in said housing and adapted to reciprocate between said formers, a driving member mounted in said housing, means connecting said driving member with each of said formers, and means detachably connecting said driving member with said blank holder, whereby
 60   said formers are oscillated and said blank holder is reciprocated in unison therewith, and means driven by said driving member for slowly advancing said formers toward said blank holder, whereby said gradually tapering blades are embedded in opposite sides of the blank in said blank holder to gradually displace the metal thereof in the form of dense compact ribs by pressure exerted substantially normal to the surface
 65   of said blank, whereby the outer surface
 70   metal of said blank is not disrupted.

75   This specification signed and witnessed this 6th day of November, A. D., 1907.
